UNITED STATES PATENT OFFICE.

GEORGE A. WEBER, OF NEW YORK, N. Y., ASSIGNOR TO THE WEBER RAILWAY JOINT MANUFACTURING COMPANY, OF NEW YORK, N. Y., A CORPORATION OF WEST VIRGINIA.

STEP-JOINT.

SPECIFICATION forming part of Letters Patent No. 744,831, dated November 24, 1903

Application filed April 15, 1903. Serial No. 152,739. (No model.)

To all whom it may concern:

Be it known that I, GEORGE A. WEBER, a citizen of the United States, and a resident of the borough of Manhattan, city, county, and State of New York, have invented certain new and useful Improvements in Step-Joints, of which the following is a specification, accompanied by drawings.

My invention relates to railroad-rail joints, but more particularly to that class known as "step-joints," wherein rails of different weight and height are supported in surface alinement.

The objects of my invention are to improve upon the construction of such step-joints and increase their efficiency, with simplicity of construction and additional strength of parts.

To these ends my invention consists of apparatus for carrying out the above objects embodying the features of construction, combinations of elements, and arrangement of parts, substantially as hereinafter fully described and claimed in this specification and shown in the accompanying drawings, in which—

Figure 1 is a side view of an uninsulated step-joint applied to rails of different weight and size. Fig. 2 is a plan view of Fig. 1. Fig. 3 is a transverse sectional view taken on the line Y Y of Fig. 2. Fig. 4 is a side elevation of the inside of a modified form of shoe-angle, showing the corrugations transverse to the length of the shoe-angle. Fig. 5 is an end view of the shoe-angle shown in Fig. 4. Fig. 6 is an end view of another form of shoe-angle. Fig. 7 is a side elevation of the inside of a modified form of shoe-angle. Fig. 8 is an end view of Fig. 7. Fig. 9 is a plan view of the shoe-angle shown in Fig. 7. Fig. 10 is a side elevation of the inside of a form of shoe-angle. Fig. 11 is a plan view of the shoe-angle shown in Fig. 10.

The rails A and B, as shown, are of different weight and height, the rail A being supported directly upon the support or angle-chair C, while in this instance a portion of the base D of the chair is provided with means integral therewith for maintaining the rails in surface. As shown, the angle-

chair is corrugated over a portion of the base. The corrugations E are of sufficient height above the level of the plane surface of the base to bring the rails into surface. The corrugations E may be formed upon the base of the angle-chair by any suitable means, and they may extend either longitudinally of the chair or transversely thereof, and they may be of any suitable or desired size and dimensions to meet the conditions required.

In Fig. 6 the corrugations are shown with angular shoulders F and flat surfaces G, while in the other figures the ribs formed by the corrugations are of curved outline.

In Figs. 7 and 8 instead of a number of corrugations it will be seen that the angle-chair is provided with a longitudinally-extending raised portion H, which may be pressed into the desired shape. The raised portion H, as shown, is hollow underneath and provided with a plane surface, affording a seat for the base of one of the rails.

In Figs. 10 and 11 instead of a number of corrugations and instead of a single raised portion but two transversely-extending raised portions or ribs I are formed upon the angle-chair, and it is obvious that many other variations of my invention may be devised. I have shown several convenient forms of constructions for the angle-chair to compensate for the differences in the height of the rails. According to my invention it will be seen that the chair is formed all in one piece and that a light, strong, and rigid construction is obtained which will withstand wear and which is simple and cheap to make.

As stated, the taller and heavier rail is supported upon the plane surface of the base of the angle-chair, while the lighter and shorter rail is supported upon the remaining raised portion of the base. Suitable means are provided for maintaining the rails in alinement, in this instance an angle-plate J being arranged at one side of the webs of the rails, while a channel-plate K is arranged at the other side of the webs. The plates J and K extend across the joint and are suitably offset vertically and horizontally to compensate for the different height of the rails and the different thickness of the web portions. As shown,

in this instance a packing-block L is inserted between the plate K and the upright of the angle-chair, while suitable bolts O are adapted to secure the parts of the joint together.

5 Obviously some features of my invention may be used without others and my invention may be embodied in widely-varying forms.

Therefore, without limiting myself to the construction shown and described, nor enumerating equivalents, I claim, and desire to obtain by Letters Patent, the following:

1. A rail-joint comprising rails of different size and height, a rail-support for the rails having a raised portion integral with the support, the rail of lesser height being supported upon said raised portion, whereby provision is afforded for maintaining the running surfaces of the rails in surface, fish-plates offset both laterally and at top and bottom to compensate for the differences in position of the remaining parts when the running surfaces of the rails are in surface and alinement, and bolts for securing the parts of the joint together, for substantially the purposes set forth.

2. A rail-joint comprising rails of different size and height, a rail-support for the rails having a corrugated portion extending over a portion of the support, the rail of lesser height being supported upon said corrugated portion, whereby provision is afforded for maintaining the running surfaces of the rails in surface, means for maintaining the rails in alinement, and bolts for securing the parts of the joint together, for substantially the purposes set forth.

3. A rail-joint comprising rails of different size and height, a rail-support for the rails having a portion formed with longitudinally-extending ribs integral with the support, the rail of lesser height being supported upon said portion formed with longitudinally-extending ribs, whereby provision is afforded for maintaining the running surfaces of the rails in surface, fish-plates offset both laterally and at top and bottom to compensate for

the differences in position of the remaining parts when the running surfaces of the rails are in surface and alinement, and bolts for securing the parts of the joint together, for substantially the purposes set forth.

4. A rail-joint, comprising in combination with rails of different size and height, of means for supporting said rails in surface consisting of a base-plate provided with a corrugated portion, the corrugations extending above the plane of the remainder of the plate, forming a step for the rail of lesser height, fish-plates, and bolts for securing the parts of the joint together, for substantially the purposes set forth.

5. A rail-joint, comprising in combination with rails of different size and height, of means for supporting said rails in surface consisting of a rail-chair having a base and an upright, the base having a corrugated portion, the corrugations extending above the plane of the remainder of the plate, forming a step for the rail of lesser height, fish-plates, and bolts for securing the parts of the joint together, for substantially the purposes set forth.

6. A rail-joint, comprising in combination with rails of different size and height, of means for supporting said rail in surface consisting of a rail-chair having a base and an upright, the base having a raised portion pressed from the material of the chair and thereby forming a hollow step for the rail of lesser height, fish-plates, and bolts extending through the webs of the rails, the fish-plates, and the upright of the chair for securing the parts of the joint together, for substantially the purposes set forth.

In testimony whereof I have signed this specification in the presence of two subscribing witnesses.

GEORGE A. WEBER.
